UNITED STATES PATENT OFFICE

152,806

DESIGN FOR A FLOODLIGHT HOLDER

William H. Klein, Great Neck, N. Y., assignor to
The Franklin Company, a firm composed of Henry Henricksen, William H. Klein, and Erasmo E. Spagnoli, Woodside, N. Y.

Application January 21, 1948, Serial No. 143,946

Term of patent 3½ years

(Cl. D48—20)

To all whom it may concern:

Be it known that I, William H. Klein, a citizen of the United States of America and a resident of Great Neck, county of Nassau and State of New York, have invented a new, original, and ornamental Design for Floodlight Holder, of which the following is a specification, reference being had to the accompanying drawing, forming part thereof, of which:

Fig. 1 is a side elevation of the floodlight holder embodying my new design.

Fig. 2 is a face plan view thereof.

I claim:

The ornamental design for a floodlight holder, as shown.

WM. H. KLEIN.
